DESIGN FOR A STAKE FOR CROQUET AND LIKE GAMES

John R. Morgan, Oak Park, Ill., assignor to Sears, Roebuck and Co., Chicago, Ill., a corporation of
New York

Application June 24, 1937, Serial No. 70,034

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Stake for Croquet and Like Games, of which the following is a specification, reference being had to the accompanying drawing, forming a part thereof.

The drawing is a perspective view of a stake for croquet and like games embodying my new design.

I claim:

The ornamental design for a stake for croquet and like games, as shown.

JOHN R. MORGAN.
